G. W. PITTMAN & W. C. BOONE.
ROPE MACHINE.

No. 23,491.

Patented Apr. 5, 1859.

UNITED STATES PATENT OFFICE.

GEORGE W. PITTMAN AND WILLIAM C. BOONE, OF BUSHWICK, NEW YORK.

IMPROVEMENT IN MACHINERY FOR LAYING ROPE.

Specification forming part of Letters Patent No. 23,491, dated April 5, 1859.

To all whom it may concern:

Be it known that we, GEORGE W. PITTMAN and WILLIAM C. BOONE, of Bushwick, in the county of Kings and State of New York, have invented certain new and useful Improvements in Machines for Laying Rope; and we do hereby declare that the following is a full, clear, and exact description of the same, reference being had to the accompanying drawings, forming part of this specification, in which—

Figure 1 is a longitudinal sectional view of a horizontal laying-machine constructed according to our invention. Fig. 2 is a transverse section of one of the fliers.

Similar letters of reference indicate corresponding parts in both figures.

Our invention relates to that description of rope-laying machine whose strand-fliers or two or more of them are arranged with their axes in line with each other.

It consists, first, in a certain method of forwarding the twist of the strands from the fliers which are farthest from the laying-point.

It consists, secondly, in a guide-ring applied, as hereinafter described, to that one of a series of fliers so combined which is farthest from the laying-block for the purpose of carrying forward toward the laying-block the forehand twist, which is given by the revolution of the said flier to a strand supplied from a spool which turns in fixed bearings outside of the fliers.

To enable others skilled in the art to make and use our invention, we will proceed to describe its construction and operation.

A A' A² are three standards constituting the principal portion of the framing of the machine, and containing the bearings for the two fliers B B', from which two of the strands c and c' are supplied, and the standard A², having attached brackets a, which support the spindle b of a bobbin C², from which the third strand c² is supplied. The hollow journal j', which forms the connection between the fliers, is supported in the middle standard A, and the journals j and j² at the opposite ends of the fliers are supported in the standards A A².

The fliers are made much longer than the bobbin, in order to prevent short bends in the

strands, and the elliptical form shown in the drawings is to be preferred. The flier-bobbins C C' have their spindles d d supported in bearings in iron cradles E E', which are provided with journals e e' to fit to bearings in the fliers, the said bearings in the fliers being concentric with the axis of the fliers and the cradles being heavy enough to hold the bobbins stationary, or nearly so, by gravitation while the fliers revolve. One journal e' of each cradle is hollow for the strand to pass through. The flier B contains the laying-block g, and it has two guides h h for the strands c² c' to pass through on the way to the laying-block. The flier B' has attached to it two guides i and m on one side for the strand c² to pass through, the guide m being a single eye, but the guide i being a ring which passes through and plays freely in an eye i', which attaches it to the flier. This ring i constitutes one feature of our invention and its operation will be presently described.

F is the capstan, by which the rope is taken up as fast as it is laid, supported in bearings attached to the standard A.

G is the driving-shaft of the machine, supported in bearings in the standards A A' A², and carrying two pulleys H and I, the former driving the two fliers by a belt k, running over a pulley J on their connecting journal j', and the other pulley I driving the capstan by means of a belt L, which passes under two guide-pulleys l l and over a pulley M, attached to the capstan.

The bobbin C² is so arranged that it will deliver its strand c² through the hollow flier-journal j². The said strand passes from the said journal to the ring i, round which it is once turned, and from the said ring it passes through the guide m, and from thence through the journal j' and the flier B, and through the guides h h in one side of the flier and into the laying-block. The strand c' passes from the bobbin C' round the bottom of its cradle E', through two guides n n, attached thereto, and through the hollow journal e' thereof, and from thence through the journal j', in which it and the strand c² take a few turns round each other and into the flier B, through the guides h h on the opposite side of the said flier to those through which the strand c² passes, and from thence to the laying-block.

The strand c passes from the bobbin C round the bottom of the cradle E , and through guides n thereon through the hollow journal e' thereof, and from thence direct to the laying-block.

The operation of laying is produced by the revolution of the fliers, which gives to the strands c c' , before they leave their respective fliers, an additional twist; but this twist is taken out in laying, leaving each strand with the same twist it had when introduced to the machine. The revolution of the flier B' also gives to the strand c^2 the same additional twist which the other strands at first receive and which is also taken out at the other end of the machine in the laying. The additional twist is given to the strand c^2 between its bobbin at the first point where it meets with friction—viz., the ring-guide i —and this twist requires to be forwarded toward the laying-point. If, instead of the ring i , a simple guide were employed, the twist would not go forward easily, but would cause a kinking of the strand between the bobbin c^2 and the said guide; but by passing the strand round a loose ring, in the manner represented in Fig. 1, the twist is caused to work its way forward, the ring turning slowly in its eye i' as the strand passes through it, and thus preventing any great friction being caused by passing the strand round it. By providing communication from one flier to the other through a hollow journal and causing the strands c^2 and c' to turn round each

other or be, as it were, laid and unlaid in passing through the said journal, each is made to help forward toward the laying-point the additional twist in the other one, and by this means and the use of the ring i the necessity of gearing for forwarding the twist is dispensed with and the machine greatly simplified.

Instead of having the two fliers connected by the journal j' , each may have a separate journal with a communication from one flier to the other through the said journals, provided the fliers are driven by gearing in such a manner that both rotate at the same speed.

We do not claim the arrangement of the fliers with their axes in the same line, nor the connection of fliers so arranged; nor do we claim, in combination with such arrangement, applying one of the bobbins without a flier, like the bobbin C^2 ; but

What we claim as our invention, and desire to secure by Letters Patent, is—

1. The laying and unloring of the strands c c^2 as they pass through the hollow journal or journals of the fliers to forward the twist, as herein described.

2. The ring-guide i' , applied, in combination with the bobbin C^2 , to the nearest flier, substantially as and for the purpose set forth.

GEO. W. PITTMAN.
W. C. BOONE.
